UNITED STATES PATENT OFFICE.

HENRY C. JONES, OF WILMINGTON, DELAWARE.

MACHINE FOR CUTTING METAL SHAPES.

SPECIFICATION forming part of Letters Patent No. 535,207, dated March 5, 1895.

Application filed January 14, 1895. Serial No. 534,895. (No model.)

To all whom it may concern:

Be it known that I, HENRY C. JONES, a citizen of the United States, and a resident of Wilmington, Delaware, have invented certain 5 Improvements in Machines for Cutting Metal Shapes, of which the following is a specification.

My invention relates to improvements in shearing machines for cutting metal beams, 10 such as I-beams, channels, angles and various other shapes. This object I attain in the following manner, reference being had to the accompanying drawings, in which—

Figure 1, is a front view of sufficient of the 15 machine to illustrate my invention. Fig. 2, is a side view. Fig. 3, is a section on the line 3—3, Fig. 1. Fig. 4, is a plan view of the lower cutter. Fig. 5, is a perspective view of one of the lower side knives. Figs. 6, 7 and 20 8, are diagram views illustrating the different movements of the machine. Figs. 9, 10 and 11, are views of modifications and different arrangements of the cutters.

The main object of the invention is to so 25 construct the machine that it will first cut the web of an I-bar, for instance, by a vertical movement and then by a lateral movement first in one direction and then the other, shear the flanges of the beam. By this means the 30 cutting is accomplished very quickly and with a single sliding head.

A A are the housings of the machine having guide ways $a a$ for the vertically reciprocating head B, hung to the crank shaft D by 35 the yoke frame $b b$ and sliding blocks b' which are adapted to the cranks of the shaft. The crank shaft D is mounted in suitable bearings in the housings A and is driven from the intermediate shaft D' through gears $d d'$, and 40 this shaft is driven from the driving shaft D² by a pinion d^2 and gear wheels d^3 . The driving shaft D² can be driven direct by an engine, its connecting rod being coupled to the crank d^4 or it may be driven from line 45 shafting if more convenient.

A' is the base on which are ways a' for the lower stationary cutters a^3 and adjustable head blocks a^2 carrying the side cutting knives. The lower dies or cutters a^3 are held 50 in place by bolts a^4 and can be removed and different sized cutters can be placed in their

stead. The cutters a^3 have detachable blades held in position by bolts a^6 , as shown in Fig. 4, so that the blades can be turned or replaced.

The head blocks a^2 are laterally adjustable 55 to accommodate different widths of beams and are moved toward and from each other by a screw A^2 having a hand wheel a^5 . This screw has a right and left hand thread and one thread is adapted to one block and the other to the opposite block so that they will move in unison toward or from each other. On each head block are blades a^7 , shown in Fig. 5, which are preferably made square in cross section and the bolt holes are so arranged in the block that the knives can be turned or reversed to present a good cutting edge.

Coupled to the upper portion of the head B is a piston rod E connected to a piston E' 70 in a cylinder E² mounted on the frame of the machine. Fluid under pressure is admitted to the space under the piston so as to counter-balance, to a certain extent, the weight of the reciprocating head B.

The head B is made hollow in the present instance and hung to a pivot bar F is a lever I carrying the upper cutting knives $i i'$. These knives are mounted in the lower portion of the lever, in any suitable manner. In the 80 present instance they are adapted to sockets and are secured in place by bolts i^2 . At the end of each long socket for the side knives are hard metal bearing plates i^3 which rest in grooves, being inserted through slots in the 85 sides.

Carried by the head B is a short crank shaft F' having a crank f on which is mounted a sliding block f' adapted to a slide way i^3 in the upper portion of the lever I. The crank 90 shaft F' is adapted to removable bearings b^2 in the head B so that the shaft can be readily inserted or detached.

On the front end of the shaft F' is a bevel wheel g meshing with a bevel pinion g' mounted on a vertical shaft G having its bearings in a bracket B' on the slide, and adapted to slide in the hub of a bevel pinion H, to which it is splined so that it will turn with the pinion. This pinion is mounted in a fixed bearing A³ 95 secured to the frame of the machine and gears with a pinion J on a shaft J' mounted 100

in bearings in the frame of the machine. This shaft J' is coupled to a gear wheel j by a clutch j' so that the shaft can be thrown into and out of gear with the gear wheel. This 5 wheel j is geared to the wheel d' which is also loose on the shaft D and is coupled thereto by a clutch d^5 which can also be thrown into and out of gear by the operator.

On each side of the frame of the machine 10 are mounted chocks S which consist essentially of a shaft s adapted to bearings s' and on each shaft is an arm s^2 and a handle s^3 . The handles can be turned in such a manner that the arms s^2 will bear directly upon the 15 rear of the head blocks a^2 , and thus take the strain off the adjusting screw A^2 , when the machine is shearing.

When the blocks are adjusted for different sizes of beams filling pieces may be inserted 20 between the blocks and the chocks if found necessary.

In Fig. 9, I have shown a modification in which two sets of knives can be adjusted in position for use, using an intermediate head 25 block a^3 and dispensing with the central upper knife i . A wedge i^6 is inserted between the two knives i^7 , i^8 and a confining screw i^4 is passed through the block into the head. This arrangement is only used when beams of the 30 smaller sizes are to be cut.

The side knives are double ended so that when one edge is worn they can be turned to present new cutting edges and it will be noticed in Fig. 1, of the drawings, that there 35 there are two sets of these knives at each side of the center knife i . By this arrangement I can use the intermediate knives as fillers, yet when a narrower I-beam is to be cut the outer knives can be detached and the intermediate knives become the side cutting knives 40 and when still smaller beams are to be cut both side knives can be removed leaving only the central knife. When other sizes are to be cut these knives may be detached and others substituted therefor and suitable wedge 45 blocks and filling pieces may be used, as shown in Figs. 10 and 11.

The operation of the machine is as follows:— If for instance an I-beam is to be cut, as shown 50 in the drawings it is mounted in position on the lower cutter and the head blocks adjusted so that the side knives of the said block will bear upon the flanges of the beam. The chocks are then turned so as to relieve the screw of 55 the pressure, the clutch d^5 is thrown into gear imparting motion to the shaft D , which will force the head B down and the upper knives will cut through the web of the beam, leaving the flanges intact. The clutch is then 60 thrown out of gear and the clutch j' thrown into gear so as to impart motion to the shaft J which will turn the short crank shaft F' carried by the head B . This crank shaft will give a lateral motion to the lever I carrying 65 the upper knives which will cut one flange of the I-beam as shown in Fig. 7, and as the cam

shaft revolves it will cut the other flange, as shown in Fig. 8, after which the clutch j' is thrown out of gear and the clutch d^5 thrown into gear to raise the head B and its knives. 70

When cutting single angle bars, T or other shapes, only one side cutting knife is used and if a machine is to be built especially for this purpose it need only have the single side motion instead of the double motion described 75 above.

In some instances the sides of the upper blades may be slightly curved, as shown in Fig. 10, to properly shear the flanges without undue crushing. 80

I claim as my invention—

1. The combination in a machine for cutting metallic shapes, of the reciprocating head, a lever pivoted thereon and carrying the upper blades, with mechanism for laterally moving 85 the lever, substantially as specified.

2. The combination in a shearing machine, of the sliding head, a pivoted lever carried thereby, blades mounted in the lever, a crank shaft carried by the head by which a lateral 90 motion is imparted to the lever, substantially as described.

3. The combination in a shearing machine for cutting metal shapes, of the base, the head blocks adjustable thereon, side blades carried 95 by the head blocks and lower blades carried by the base, a reciprocating head, a lever pivoted thereto, upper blades secured to the lever, mechanism for laterally moving the lever so that the blades will not only cut on the 100 face but on the sides, substantially as described.

4. The combination of the frame of the machine, the reciprocating head adapted to the frame, a pivoted lever hung to the head, means 105 for laterally moving the lever, blades carried by the lower portion of the lever, a base, head blocks adjustably mounted on said base between which the metallic shape is held, and chocks back of each head, substantially as 110 described.

5. The combination of the frame, the sliding head, mechanism for reciprocating said head, a lever pivoted to the head, blades carried thereby, a crank shaft adapted to impart 115 motion to the lever, a vertical shaft carried by the head and geared to the crank shaft, a pinion splined to the said shaft, so that the shaft will turn with the pinion but will slide therein, a driven shaft geared to the pinion, 120 substantially as described.

6. The combination of the frame, the base, the lower central knife secured to the base, the laterally adjustable head blocks mounted on the base, knives carried thereby, with a 125 vertically reciprocating head, a laterally vibrating lever thereon, with upper knives adjustably secured to the lever, substantially as described.

7. The combination in a metal shearing 130 machine, of the reciprocating head, a lever thereon recessed to receive blades, detachable

central blade, side blades and means for securing said blades in position, substantially as described.

8. The combination in a metal shearing machine, of the reciprocating head, the lever pivoted thereto having pockets, central and side blades adapted to said pockets, said side blades being shaped at their opposite ends so that they can be reversed, substantially as described.

9. The combination in a beam shearing machine, of the base, the vertical reciprocating head, pivoted lever thereon carrying the upper blades, the lower blades mounted on the base, side knives also mounted on the base, the sides of the upper and lower blades for cutting the web being shaped so as not to im-

pinge upon the flange during the vertical cutting, substantially as described.

10. The combination in a beam shearing machine, of the lower knives and side blocks, with a reciprocating head, a laterally vibrated lever carried thereby, knives on said lever, the cutting sides of said knives being curved to properly shear the flange of the beam without crushing when the lever is vibrated, substantially as described.

In testimony whereof I have signed my name to this specification in the presence of two subscribing witnesses.

HENRY C. JONES.
